UNITED STATES PATENT OFFICE.

ADELBERT E. OSBORN, OF WACO, TEXAS, ASSIGNOR TO THE MODEL MACHINE COMPANY, OF SAME PLACE.

RATCHET-WRENCH.

SPECIFICATION forming part of Letters Patent No. 295,797, dated March 25, 1884.

Application filed December 31, 1883. (No model.)

To all whom it may concern:

Be it known that I, ADELBERT E. OSBORN, a citizen of the United States, residing at Waco, in the county of McLennan and State of Texas, have invented new and useful Improvements 5 in Ratchet-Wrenches, of which the following is a specification.

This invention relates to improvements in ratchet-wrenches wherein a handle carrying a 10 rotating head having jaws to grasp a nut is provided with pivoted pawls, so that by oscillating the handle the pawls serve to rotate the head and screw or unscrew the nut, bolt, or other device.

15 The objects of my invention are to provide a rotating head of novel construction, whereby the nut-grasping jaws can be adjusted in the head for nuts or bolts of varying sizes; to provide simple and efficient means for changing 20 the position of the nut-grasping jaws in the rotating head, and to provide simple means for confining the said jaws in position. These objects I accomplish by the construction and combination of devices hereinafter described 25 and claimed, reference being had to the accompanying drawings, illustrating my invention, in which—

Figure 1 is a plan view of a ratchet-wrench constructed in accordance with my invention; 30 Fig. 2, a plan view of the same with the detachable plate removed, which serves to confine the rotating head in position; Fig. 3, a longitudinal sectional view of Fig. 1; Fig. 4, a perspective view of the rotating plate which 35 carries the nut-grasping jaws and their adjusting device, and Fig. 5 a perspective view of one of the jaws.

Referring to the drawings, the number 1 indicates a metallic plate rigidly secured at one 40 end to a suitable handle, 2, and having at its outer end a circular opening which receives one side of the rotating head 3, said plate having two recesses, 4 and 5, the one 4 serving to receive the actuating-pawls 6, and the one 5 45 serving as a bearing or seat for one end of the detachable plate 7, which is provided at its other end with a circular opening receiving the other side of the rotating head. The periphery of the head, centrally between the opposite sides, 50 is provided with a notched flange forming

ratchet-teeth 8, said flange resting between the metallic plates, so that the head is securely held against displacement when the plate 7 is attached by the screws 9, while said head can be freely rotated in either direction by means of the pawls 6, which are pivoted at one end in the recess 4 of the plate 1, as before stated, said pawls being connected by a coiled spring, 10, which draws their free ends upon the ratchet part of the head, so that they engage therewith and rotate the head when the handle is swung or oscillated, as usual in this class of wrenches. The rotating head is provided with an elongated opening, the ends 11 of which constitute seats for the shanks 12 of the 60 nut-grasping jaws 13, while the opposite side edges of said opening are each provided with two seats or recesses, 14 15 16, also for receiving the shanks of the jaws, in such manner that the jaws can be changed about in the 65 elongated opening of the head to rest in any of the seats or recesses alluded to for small or large bolts or nuts. The shanks of the jaws are provided with shouldered heads having screw-sockets 17, with which respectively engage the right and left hand screw-threads of the jaw-adjusting rod 18, the latter being provided at each end with a finger-piece, 19, and journaled adjacent thereto in ears 20, formed on a circular plate, 21, having a rectilinear 70 slot, 22, and loosely resting upon one side of the rotating head, said plate being of a larger diameter than the sides of the head, so as to project over upon the detachable plate 7, as in Fig. 3. The rotating eared plate is confined in place on the rotating head, and the detachable plate by means of the shouldered heads of the jaws resting over the side edges of the slot 22 in the plate, and the jaws engaging with the opposite side of the head, as 75 will be clearly understood by Fig. 3. By turning the screw-rod 18 in the proper direction to cause the jaws to approach each other and leave their seats in the rotating head, the plate 21 can be rotated, carrying with it the jaws, 80 said plate being turned until the shanks of the jaws are opposite the desired set of seats or recesses in the head into which it is desired to adjust the jaws, after which the screw-rod is 85 properly rotated to cause the jaws to recede 90 95 100

from each other and enter the seats or recesses opposite to which they have been brought by the adjustment of the rotating plate. The jaws will of course always move in a right line, owing to the rectilinear shape of the slot in the rotating plate, and by changing the jaws from one set of seats or recesses to another in the edges of the opening in the head the capacity of the wrench for grasping large or small objects can be quickly and conveniently changed. If the rotating plate be so adjusted as to bring the shanks of the jaws upon the seats in the ends of the opening in the head, and the screw-rod turned to bring the shanks together until the jaws entirely leave the side of the rotating head and come within the edges of the spring, the rotating plate can be lifted from its place and the jaws thereby removed from the head, if such should be desired for any purpose, such as for repairs. A cam, 23, is pivoted to a stem, 24, between the jaws, such stem projecting through the detachable plate 7, and provided with a finger-piece, 25, in such manner that by properly adjusting the cam either one of the pawls can be thrown out of engagement with the ratchet of the rotating head, thus permitting the latter to be rotated in the direction required to screw or unscrew a nut, bolt, or other object. As regards the rotating head, the novelty consists in its irregular elongated opening, the edges of which are formed into a series of sets of seats or recesses, 11, 14, 15, and 16, for the shanks of the jaws, whereby the jaws can be changed about in the said opening through the medium of the loose rotating plate, thereby adjusting the jaws into any set of the seats or recesses to vary the capacity of the wrench without subjecting the screw-rod to undue strain, as the walls of the seats or recesses re-

sist all outward pressure of the jaws when screwing or unscrewing a nut or other object.

The structure, as a whole, is simple and efficient, and provides a ratchet-wrench which will be found very useful for the purpose for which such wrenches are usually employed.

Having thus fully described my invention, what I claim is—

1. The combination of the rotating head having an irregular-shaped opening, forming a series of sets of seats or recesses, with the movable jaws having shanks, and means for moving the jaws about in the said opening and adjusting them to any set of the seats or recesses, substantially as described.

2. The combination of the rotating head having an irregular-shaped opening, forming a series of sets of seats or recesses, with the movable jaws having shanks, the rotating plate at one side of the head, provided with a slot, and an adjusting-screw carried by the plate and engaging the shank of the jaws, substantially as described.

3. The combination of the rotating head held to rotate between the plates of the handle, and provided with an irregular shaped opening, forming a series of sets of seats or recesses, with the jaws having shouldered heads, the rotating plate at one side of the head, provided with the rectilinear slot, and the screw-rod carried by the rotating plate and engaging the shouldered heads of the shanks, substantially as described.

In testimony whereof I have hereunto set my hand in the presence of two subscribing witnesses.

ADELBERT E. OSBORN.
